(57) **CLAIM**

The ornamental design for an angled grip, as shown and described.

DESCRIPTION

FIG. 1 includes a perspective view of a first embodiment of an angled grip.

FIG. 2 includes another perspective view thereof.

FIG. 3 includes a first side view thereof.

FIG. 4 includes a second side view thereof.

FIG. 5 includes a front view thereof.

FIG. 6 includes a back view thereof.

FIG. 7 includes a perspective view of a second embodiment of an angled grip.

FIG. 8 includes another perspective view thereof.

FIG. 9 includes a bottom view thereof.

FIG. 10 includes a side view thereof.

FIG. 11 includes a front view thereof.

FIG. 12 includes a back view thereof; and,

FIG. 13 includes a side view of a firearm with an angled grip. The broken lines in the figures depict portions of the angled grip that form no part of the claimed design. The broken line depiction of a rifle in FIG. 13 forms no part of the claimed design.

The angled grip finds use as an accessory for firearms, paintball guns, and other projectile weapons.
